ATTORNEY

UNITED STATES PATENT OFFICE.

JULIO H. RAE, OF MILFORD, DELAWARE.

BOILER-FEED.

SPECIFICATION forming part of Letters Patent No. 404,730, dated June 4, 1889.

Application filed February 28, 1889. Serial No. 301,503. (No model.)

To all whom it may concern:

Be it known that I, JULIO H. RAE, a citizen of the United States, residing at Milford, in the State of Delaware, have invented new and useful Improvements in Boiler-Feed, &c., of which the following is a specification.

This invention relates to an apparatus by means of which the exhaust-steam of an engine can be returned into the boiler to which the engine is connected, so that the heat of the exhaust-steam is not wasted.

The peculiar construction of my apparatus is pointed out in the following specification and claim, and illustrated in the accompanying drawing, which represents a longitudinal vertical section.

In the drawing, the letter A is a tank of sufficient strength to withstand the pressure to which it may be exposed. This tank connects by a pipe B with the exhaust-port of a steam-engine, and by a pipe C with the steam-boiler D, from which the steam-engine derives its live steam. This feed-pipe C connects with the barrel of a pump E, the plunger of which may be operated from the steam-engine or from any suitable source of power. In the inner end of the pump-barrel is a check-valve a, and the feed-pipe C is provided with two check-valves b b'.

F is a spray-pipe, which connects with a pump G, that serves to draw water from a well and force it into said spray-pipe and through a rose c, secured to the end of this pipe. This rose is situated in a chamber d, formed in the feed-pipe C.

When the apparatus is in operation, the

exhaust-steam accumulated in the tank A is drawn into the pump E and driven therefrom through the feed-pipe C, and as it passes the spray-chamber d it is condensed and then forced into the boiler D.

It will be readily seen that by this apparatus all the heat (or nearly so) of the exhaust-steam is utilized, and the great waste of heat which takes place when the exhaust-steam is permitted to escape into the open air is avoided. At the same time the pump E can be made of such a capacity that during the operation of the apparatus the pressure in the tank A never rises much, if anything, above the atmospheric pressure, so that the exhaust from the steam-cylinder is not obstructed.

What I claim as new, and desire to secure by Letters Patent, is—

The combination, with a steam-boiler and a tank for the reception of exhaust-steam from an engine, of a pump communicating with said tank, a valved feed-pipe leading from said pump to the boiler, and a water-spraying pipe discharging into the feed-pipe between the tank and the boiler, whereby the exhaust-steam is drawn from the tank, forced into the feed-pipe, condensed therein, and forced into the boiler, substantially as described.

In testimony whereof I have hereunto set my hand and seal in the presence of two subscribing witnesses.

JULIO H. RAE. [L. S.]
